UNITED STATES PATENT OFFICE

LOUIS BORTEN, OF PHILADELPHIA, PENNSYLVANIA

VALVE CONSTRUCTION

Application filed March 30, 1929. Serial No. 351,252.

This invention relates to float valves for controlling the inflow of liquid to a receptacle as a flush tank associated with a water closet.

An object of the invention is to improve constructions of this character.

A further object is to provide an inflow pipe and valve so constructed and related as to insure a positive and complete closing of the valve on its seat.

10 A further object is to provide a float valve construction all of the damagable parts of which are readily accessible and easily renewed.

The above objects are accomplished by providing an inflow pipe having a spout extending therefrom and preferably bent downward at its outer end. An external valve is provided for closing the open end of the spout and said valve is in turn controlled by 20 a float in any suitable manner, one manner being by attaching the float to an arm which is pivoted to a stationary member, as to the inflow pipe, upon which the valve member, which may be in the nature of a disk of 25 yieldable material, is mounted in such position that when the liquid in the tank rises to a certain level, the valve will be closed against the end of the spout and in order that a positive closing of the end of the spout by the

30 valve may be insured, the spout may be formed with a circumferential bead which will contact with and somewhat depress the material of the valve when the said valve is pressed against said bead. The disk may be 35 held in position by a flanged annular member secured to the arm and the disk may be removed and renewed whenever, for any reason, this may be desired.

In the drawings:

40 Figure 1 is a section through a tank showing the inflow pipe and the associated valve constituting the subject of my invention.

Figure 2 is a vertical section through the inflow pipe showing the relation of the valve 45 to the spout.

Figure 3 is a detail perspective view showing the beaded discharge end of the spout.

Figure 4 is a detail plan view of the valve carrying arm showing the mounting of the 50 valve disk thereupon.

Referring to the drawings by reference numerals, 10 designates a tank of the type commonly known as a flush tank and 11 designates the inflow pipe associated therewith, 12 is a spout extending therefrom and having a down curvature toward its outer end. 13 is a pivoted arm upon which a valve construction 14 is mounted in position to be brought against the end of the spout 12 when the level of the fluid in the tank rises to a 60 certain predetermined level.

The inflow pipe 11 is provided with a central bore 15 which communicates with the bore 16 of the spout 12 providing a continuous passageway to the end of said spout. A 65 bracket 17 is provided on the inflow pipe and extends at right angles thereto and to this bracket is pivotally secured an arm 18 by means of the pivot pin 19 which is extended through a loop 20 in the end of the 70 bracket 17 and through apertures in spaced members 21 secured to the arm 18. These spaced members constitute a support for the valve construction which consists of a cup like member 22 soldered or otherwise secured to the spaced members and having a closed bottom and a circumferential flange 23 at its upper edge.

Within the cup-like member is mounted a disk-like member 24 which may be in the nature of a washer of yieldable or resilient material as fibre, rubber or the like. Cooperating with this disk and extending from the end of the spout is a bead 25 extending circumferentially of the end of the spout. The 80 arm 18 is provided at its free end with a float 26, which, under the influence of the change of level in the liquid in the tank, will open or close the end of the spout 12 as the case may be.

The pin 19 is of a construction to be readily removable, being slightly tapered from one end to the other and at the smaller end being provided with a kerf 27 so that the legs formed thereby may be bent in opposite directions to prevent dislodgment of the pin under ordinary stresses; the pin, however, being removable under a comparatively slight force or by a pull thereupon with a suitable tool, as a pair of pliers.

Attention is to be called to the fact that the parts of the valve construction lie on the outside of the intake pipe and are readily accessible to an attendant for regulation of the same. The washers 24 are readily removable and replaceable and in case the arm or the space members attached thereto should become mutilated or worn or should otherwise get out of commission the pin 19 may be readily removed in the above manner and the whole valve construction replaced or repaired as the case may be. The arm 18 is threadedly connected with the spaced members as shown at 28 so that these parts may 15 one be renewed without the renewal of the other when this may become desirable.

The apparatus illustrated may be modified or changed in various ways within the scope of the invention herein set forth and I do not wish to be limited in the scope of the invention except as I shall be limited by the appended claims.

I claim:—

1. A float valve organization comprising an upstanding inlet pipe, a pipe extending laterally from the standing pipe and curved downwardly, a hinge below the lateral, an arm pivoted to the hinge and extending beneath the end of the lateral, a closing member carried by the arm in position for contact with the end of the lateral and a buoy carried at the end of the arm.

2. A float valve organization comprising an upstanding inlet pipe, a pipe extending laterally from the standing pipe and curved downwardly terminating in a plane perpendicular to the axis of the standing pipe, a hinge below the lateral, an arm pivoted to the hinge and extending beneath the end of the lateral, a resilient closing member carried by the arm in position for contact with the end of the lateral and a buoy carried at the end of the arm.

3. A float valve organization comprising an upstanding inlet pipe, a pipe extending laterally from the standing pipe and curved downwardly and having an annular bead about the outlet orifice, a hinge below the lateral, an arm pivoted to the hinge and extending beneath the end of the lateral, a closing member carried by the arm in position for contact with the end of the lateral and a buoy carried at the end of the arm.

4. A float valve organization comprising an upstanding inlet pipe, a pipe extending laterally from the standing pipe and curved downwardly, a hinge below the lateral, an arm pivoted to the hinge and extending beneath the end of the lateral, a resilient closing member carried by the arm in position for contact with the end of the lateral and a buoy carried at the end of the arm.

5. A float valve organization comprising an upstanding inlet pipe, a pipe extending laterally from the standing pipe and curved
